UNITED STATES PATENT OFFICE.

CHARLES VAN DENBARK, OF LINCOLN, NEBRASKA.

HARNESS-TRACE.

No. 877,683.

Specification of Letters Patent.

Patented Jan. 28, 1908.

Application filed December 27, 1906. Serial No. 349,672.

To all whom it may concern:

Be it known that I, CHARLES VAN DENBARK, a citizen of the United States, residing at Lincoln, in the county of Lancaster and State of Nebraska, have invented a new and useful Harness-Trace, of which the following is a specification.

This invention relates to improvements in harness traces of that class which employ leather and metallic chains in their construction.

The object of the invention is to provide a trace of this kind that will combine all of the advantages of a leather trace with the strength and permanence of a metallic chain construction.

It is well known that ordinary leather traces are liable to stretch unequally in service and that the inequality in the length of traces thus occasioned is often the cause of injury and discomfort to the horse.

In this invention a metallic chain is housed within a leather trace in such a way as to be entirely concealed and protected from the weather and the trace presents no external indication of this reinforcement.

The invention consists in the novel combination, construction and arrangement of parts hereinafter fully described, claimed, and illustrated in the accompanying drawings, in which,

Figure 1 is a side elevation of a trace constructed in accordance with this invention; Fig. 2 is a transverse section of the trace shown in Fig. 1; Fig. 3 is a longitudinal central section of Fig. 1; and Fig. 4 is a longitudinal central section of a hames-tug constructed in accordance with this invention.

Referring to the drawings, the leather sheath or portion 1 of the trace is provided with a longitudinal pocket formed by sewing or by fastening by other means between the two opposite outer layers, two layers 2, 2, extending along the opposite edges of the trace leaving a clear space between. The several layers forming the trace are folded up to form a loop 3 at one end of the trace, into which the said pocket opens. The loop 3 is adapted to receive the pintle 4 of the cock-eye 5.

Fitting snugly within the pocket of the trace is the chain 6. Each link of this chain is formed in a well known manner from a single piece of sheet metal bent in the form of a loop and having substantially pear-shaped apertures at each end thereof registering

with each other and adapted to contain the looped portion of the adjoining link. The pintle of the cock-eye passes through the loop of one of the terminal links of the chain and thus secures the chain longitudinally in a fixed position within the pocket of the trace. The free end of the chain terminates within the outer end of the trace and is concealed from view by a leather closure at the end of the pocket.

Holes 7 adapted to receive the tongue of a trace-buckle are punched through the trace near the outer end thereof and positioned to register with apertures in the chain links so that the buckle tongue will be brought into contact with the links in such a manner that any forward pull upon the buckle will be divided between the leather portion of the trace and the chain and will be transmitted directly and independently in each case to the cock-eye.

The trace buckle shown in the drawings is attached to one end of the hames tug and is of a well known design particularly adapted to the purpose for which it is here used, as any forward pull upon the buckle binds it together against the opposite sides of the trace and presses the side walls of the contained pocket against the chain, thus binding the trace and chain together so that the whole pull upon the buckle does not come upon its tongue.

It is evident that this improved method of reinforcing leather may be used for many different purposes besides that of forming a trace. One of the many ways in which this invention may be applied is in constructing hame tugs, as shown in Fig. 4 of the drawing. This tug has a central longitudinal pocket opening into leather loops at each end of the tug. A chain fits snugly within this pocket, and is fastened at one end to one member 9 of a trace buckle extending through one of the loops, and at the other end to a steel clip or attaching device 8 within the loop, adapted to receive the pin or bolt used to attach the tug to the hame.

It is obvious that by this construction of a trace or a hame the leather sheath and its contained chain sustain the tension jointly and severally, and that either may break without impairing the efficiency of the other.

What is claimed is:

1. A device of the character described comprising a leather portion having a longitudinal pocket therein, and a chain disposed

longitudinally within the pocket and secured at its ends thereto, said chain comprising a plurality of links each consisting of a looped apertured member, the loop of each member extending through the aperture of an adjoining member, said leather portion having openings registering with certain of the loop receiving apertures for the reception of a buckle tongue.

10 2. A device of the character described comprising a leather portion having a longitudinal pocket and provided with looped ends, a clip within one of the loops and having spaced ends, and a chain disposed longitudinally within the pocket and extending

between and secured in said ends, said chain consisting of links each comprising a loop having registering apertures, the aperture of each link being designed to receive the loop of an adjoining link, the leather portion of 20 said device having openings registering with certain of the loop receiving apertures of the chain.

In testimony that I claim the foregoing as my own, I have hereto affixed my signature 25 in the presence of two witnesses.

CHARLES VAN DENBARK.
